United States Patent Office.

JOHN BAUMGARTNER AND LAWRENCE ANGSTER, OF NEWARK, NEW JERSEY.

Letters Patent No. 70,780, dated November 12, 1867.

IMPROVED HAM-SLICING HOLDER.

The Schedule referred to in these Letters Patent and making part of the same.

TO ALL WHOM IT MAY CONCERN:

Be it known that we, JOHN BAUMGARTNER and LAWRENCE ANGSTER, both of Newark, in the county of Essex, and State of New Jersey, have invented a new and useful Ham-Slicing Holder; and do hereby declare that the following is a full, clear, and exact description of the same, reference being had to the accompanying drawings, making part of this specification, of which—

Figure 1 is a plan or top view, and

Figure 2 an end elevation.

This invention relates to a novel device for holding a ham of bacon steadily in position while the same is being sliced, and consists of the following parts, viz:

A is a platform, which may be fastened to a chopping-block or table by any proper means; B is a bifurcated arm attached to the side of the platform A, and extending a short distance above its surface for reception of one end of a curved hand-lever, C, said hand-lever being pivoted to the arm B at D, and extending over beyond the platform and against an upright rack E, whose teeth e hold the lever down on the object to be sliced. This lever C is serrated on its under side at e, and carries a sliding hinge-brace, F G, the part F of said brace being slotted for reception of the lever C, on which it slides, while at its lower end it forms a hinge-joint, f, with the brace G, which abuts against the ham of bacon H, or other object to be sliced.

The operation of our invention is as follows: The lever C being thrown backward, as shown in dotted lines, (see figs. 1 and 2,) and the ham of bacon H placed on the platform A, we next turn the lever over the ham and against the rack E; we now adjust the hinged brace F G by placing the part F in the serrated or under side e of the lever, and the foot or brace G against the ham of bacon, and we press the lever C down to the desired tension, and set the same in the teeth e of the rack E. The ham of bacon, being now held firmly in position by means of the arm B, brace F G, and lever C, is ready for being sliced.

Having described our invention, we would remark that where ham is sold in small quantities, our invention will be found of great convenience to butchers and grocers, as well as for domestic purposes, for slicing ham and other meats for frying.

What we claim, and desire to secure by Letters Patent, is—

The guard or arm B, the brace F G, the lever C, and rack E, operating together in manner substantially as and for the purposes described and set forth.

In testimony whereof we have hereunto set our signatures this 28th day of September, A. D. 1867.

JOHN BAUMGARTNER,
LAWRENCE ANGSTER.
